UNITED STATES PATENT OFFICE

JOHN C. MILLER, JR., OF CHICAGO, ILLINOIS, ASSIGNOR, BY MESNE ASSIGNMENTS, TO THE LAKE ERIE CHEMICAL COMPANY, OF CLEVELAND, OHIO, A CORPORATION OF OHIO

VAULT PROTECTION

Application filed February 20, 1929. Serial No. 341,354.

This invention relates to vault protection devices intended to supplement the protection afforded by alarm systems and time locks by delaying an attempt at forcible entry either by supplemental locking means actuated by an unauthorized disturbance of the regular lock or by discharging a noxious gas into the vault by similar means. It is, accordingly, a principal object of the present invention to provide an improved operating or restraining mechanism for a re-lock or gas bomb, the disturbance or injury of which will release or actuate the protective device. The desired result is preferably obtained by forming a tensioned network of wires over the more vulnerable portions of a closure and so connecting this network of tensioned wires to the actual bomb or re-locking mechanism as to restrain such mechanisms from operation. The particular form of such protective agents is immaterial to the present invention, so that a gas bomb as illustrated in my earlier application, Serial No. 302,961 filed Aug. 30, 1928, has been chosen to illustrate the application of the present invention.

It is an important object of this invention to provide a thermally responsive pulley mounting and anchor for the ends of individual tensioned wires, incorporated in the above mentioned network, that will normally hold said network system under tension but will release said tension at a predetermined temperature. In order to render the device more promptly responsive to undue heating of the vault door it is made in such a way as to assist in the conduction of heat from the door surface to the thermally responsive element. Such a device is particularly desirable because of the tendency to attack the more difficult vault closures by means of a burning or cutting torch in order to cut a hole in the door to render the locking mechanism accessible to tampering, or even to cut an opening big enough for actual entry.

Other and further important objects of this invention will be apparent from the disclosures in the specification and the accompanying drawings.

This invention (in a preferred form) is illustrated in the drawings and hereinafter more fully described.

On the drawings:

Figure 1 is an elevation of a vault door 55 equipped with a tensioned wire network embodying the features of this invention.

Figure 2 is a fragmentary showing of a door having a slightly modified wiring layout. 60

Figure 3 is an end elevation of one of the thermally responsive pulley mounts and wire anchors.

Figure 4 is a vertical cross-section of the device of Figure 3. 65

Figure 5 is a cross-section on the line V—V of Figure 4.

Figure 6 is a cross-section on the line VI—VI of Figure 4.

Figure 7 is a detail of one of the movable 70 pulleys.

As shown on the drawings:

A fragmentary showing of a vault vestibule 10 is associated with a vault door 11 in Figure 1, the door being of the common stepped joint type with sliding locking bolts 12, on each edge, the bolts on each edge being united by separate bars 13. The front side bar 13 is locked by duplicate lock boxes 14 in a manner well known to those skilled in the art. The top and bottom groups of bolts are operated by vertically sliding bars 15. The sliding bars 15 are provided with rack teeth engaged by pinions 16 which in turn engage stub sliding bars 17 which operate the groups of bolts on the sides of the door in unison with the top and bottom sets of bolts. The foregoing structure has been selected for illustrative purposes only and forms no part of the present invention. 85

As the most vulnerable portions of the vault locking mechanism are the boxes 14, the sliding bars 15 and 17, and a time lock 18, and bolt 19, if provided, these parts are desirably closely covered or approached by the wiring network of this invention. 90

A number of loose or unsupported pulleys 20 having straps 21 engaged by anchor wires 22 are incorporated in the wiring diagrams. The anchor wires 22 extend to the anchor 100

fittings shown in Figure 3, which comprise a body 23 mounted where desired by screws 24 and having a central aperture 25 to receive a cylindrical shell 26 closed at its outer end 5 and provided with a groove 27 and an aperture 28 to receive the end of one of the anchor wires 22, the extreme tip of the wire being given a right angle bend and inserted in the aperture 28 after which the wire is 10 wrapped around in the groove 27 several times to place a torque strain on the shell 26 when the wire 22 is under tension. The shell is soldered in place in the body 23 with a fusible alloy 29 having a low melting point, preferably around 160 to 165° F. Alloys such as are commonly used in automatic sprinkler heads for fire protection form a commercial 15 illustration of the type preferred, the physical characteristics of the alloy being the controlling factor. The shell 26 is provided with a helical groove 30 to facilitate the distribution of the solder throughout the length of the body 23. The body 23 is also provided with a shoulder 31 to position a pulley 32 thereon, which pulley is retained in place by a snap ring 33 seating in a groove 34 on the body.

The wiring network proper may be varied in arrangement to suit the requirements of 30 individual installations as suggested in Figures 1 and 2. In Figure 1, an anchor wire 22 for a loose pulley 20, has one end anchored as before described, to one of the anchor fittings conveniently designated on the drawing 35 as 35, this fitting being mounted near the lower left-hand corner of the inner door panel. A wire 36 is anchored to another fitting 37 from which the wire leads over the pulley 20, and upwardly to another loose pulley 20 40 anchored to a fitting 38 just to the left and above the time lock 18, downwardly again to a third loose pulley 20 anchored to a fitting 39, and again upwardly through a bomb release mechanism 40, described in my copending application previously mentioned, and thence about two other loose pulleys having 45 anchors 41 and 42, the wire then passing over a pulley 32 on the anchor 42 to another anchor pulley on another anchor 43 located 50 in the upper right-hand corner of the door panel. From the pulley on the anchor 43 the wire extends downwardly over another pair of loose pulleys 44 one of which is attached to the anchor 43 and the other to an anchor 45. The wire 36 then passes around a loose pulley 46 adjacent the lower lock box 14 and is looped around anchor pulleys 47 and 48 adjacent the right-hand side of the time lock 18, thence passing over a loose pulley 49 55 anchored at 50 adjacent the upper lock box 14, from the pulley 49 the wire passes downwardly around a loose pulley 51 anchored at 52 and the end of the wire is then attached to an anchor 53.

60 In the foregoing description the anchor

fitting of Figure 3 has been referred to by a series of reference numerals in order to assist in tracing the wire 36 on the drawing and it is to be understood that the same type of fitting is referred to in each case, it sometimes being used without the pulley 32.

70 The bomb release mechanism 40 referred to is connected by means of a Bowden wire 54 to a bomb 55, as shown in Figure 1, the exact details of construction having no bearing 75 on the present invention, it being understood that a release of the tension in the wiring network serving to permit the operation of the bomb mechanism. The bomb 55 is shown, in this instance, on the door for the purpose of 80 simplicity, but it is to be clearly understood that the Bowden wire 54 may be connected, if desired, to a firing pin mechanism as shown in my above-mentioned copending application, which mechanism is adapted to set off a bomb disposed in a suitable location off the door proper.

85 In the fragmentary showing of Figure 2, one end 56 of a wire 57 is anchored to a fitting 58 and is led over a loose pulley 59 which in turn is anchored at 60 by the anchor wire 22. The wire 57 then passes over pulleys 32 on anchors 61 and 62 and the end 63 thereof forms an anchor for a loose pulley 64. Another wire 65 is looped over the loose pulley 64 and leads to other parts of the door.

90 In use, the wiring system is set up taut with an initial tension and as so stretched tight it serves to restrain the bomb release mechanism. Should the wire 36 be severed 95 at any point or should any of the pulley anchor wires 22 be severed the whole system goes slack, thus releasing the bomb operating mechanism. It is conceivable, however, that in attempting to burn a hole through 100 the door the wires 36 or 22 might not be directly in the path of the flame. However, a cutting torch powerful enough to penetrate 105 steel in doing so actually melts the steel, the heat generated being transmitted through 110 the material of the door until it reaches one or more of the anchor fittings shown in Figure 3. As the solder or alloy 29 is chosen with 115 a low melting point like a fusible fire plug, the heat melts the solder in the body 23 and permits the tension in the wiring network to 120 rotate the shell 26 in the body 23 thus releasing the initial tension in the wiring network with a consequent release of the bomb operating mechanism.

125 It will thus be seen that I have provided an improved vault protective system sensitive both to undue heat and mechanical injury and one that has a wide latitude of arrangement to suit individual installations.

130 I am aware that many changes may be made, and numerous details of construction may be varied through a wide range without departing from the principles of this invention, and I therefore do not purpose lim-

iting the patent granted hereon, otherwise than necessitated by the prior art.

I claim as my invention:

1. A vault protective system, comprising a normally tensioned wiring network, a series of fixed and movable pulleys over which the wiring is passed, and anchors for said movable pulleys comprising an apertured body, a shell mounted for rotation therein but soldered in place by a low fusing point solder, and a connection from said movable pulleys adapted to be wrapped around said shell and secured thereto in such a way as to produce a twisting force thereon.
- 15 2. A vault protective system, comprising a normally tensioned wiring network, a series of fixed and movable pulleys over which the wiring is passed, and anchors for said movable pulleys comprising an apertured body having means thereon adapted to support said fixed pulleys, a shell mounted for rotation therein but soldered in place by a low fusing point solder, and a connection from said movable pulleys adapted to be wrapped 20 around said shell and secured thereto in such a way as to produce a twisting force thereon.
- 25 3. A vault protective system, comprising a normally tensioned wiring network, a series of fixed and movable pulleys over which the wiring is passed, and anchors for said movable pulleys comprising an apertured body, a rotatable member mounted in said body aperture, a fusible connection between said body and member adapted to restrain 30 the rotation of said member, and a connection from said movable pulleys to said member adapted to cause rotation thereof.
- 35 4. A vault protective system, comprising a normally tensioned wiring network, a series of fixed and movable pulleys over which the wiring is passed, and anchors for said movable pulleys comprising an apertured body having means thereon adapted to support said fixed pulleys, a rotatable member 40 mounted in said body aperture, a fusible connection between said body and member adapted to restrain the rotation of said member, and a connection from said movable pulleys to said member adapted to cause rotation thereof.
- 45 5. A thermally responsive anchor for the purposes described, comprising an apertured body, a shell mounted therein for rotary movement, a fusible connection between said shell and said body adapted to normally hold 50 said shell stationary, and means for imposing a twisting strain on said shell whereby upon fusing of said connection the twisting strain will be released by the rotation of said shell.
- 55 6. A thermally responsive anchor and pulley mounting for the purposes described, comprising an apertured body, a pulley mounted on said body, a shell mounted therein for rotary movement, a fusible connection 60 between said shell and said body adapted to

normally hold said shell stationary, and means for imposing a twisting strain on said shell whereby upon fusing of said connection the twisting strain will be released by the rotation of said shell.

In testimony whereof I have hereunto subscribed my name at Chicago, Cook County, Illinois.
